CLAIM

The ornamental design for a texturizing scissor and comb combination, as shown and described.

DESCRIPTION

FIG. 1 is an open top elevational view of the upper and lower member of the combination texturizing scissor and comb with angled handles and a raised thumb rest of my new design.

FIG. 2 is the reverse top open elevational view of the upper and lower member of the texturizing scissor and comb with angled handles with raised thumb rest of my new design.

FIG. 3 is a top closed elevational view of the upper and lower member of the texturizing scissor and comb combination with angled handles and raised thumb rest of my new design.

FIG. 4 is a side open elevational view of the upper and lower member of the texturizing scissor and comb combination with angled handles and raised thumb rest of my new design.

FIG. 5 is the reverse side elevational view of the lower member of the texturizing scissor and comb combination with angled handles of my new design.

FIG. 6 is the reverse side elevational view of the upper member of the texturizing scissor and comb combination with angled handles and texturizing teeth as shown of my new design; and,

FIG. 7 is a side elevational view of the lower member of the texturizing scissor and comb combination with angled handles and a raised thumb rest of my new design.
